UNITED STATES PATENT OFFICE.

CHARLES DOWNING, OF CHICAGO, ILLINOIS, ASSIGNOR TO AMERICAN CAN COMPANY,
OF NEW YORK, N. Y., A CORPORATION OF NEW JERSEY.

ELECTRICALLY-DRIVEN CAN-TESTER.

1,072,837:

Specification of Letters Patent.

Patented Sept. 9, 1913.

Application filed March 29, 1911. Serial No. 617,568.

To all whom it may concern:

Be it known that I, CHARLES DOWNING, a citizen of the United States, residing in Chicago, in the county of Cook and State of Illinois, have invented a new and useful Improvement in Electrically-Driven Can-Testers, of which the following is a specification.

This invention relates to improvements in electrically-operated-can-testers, and consists in the means employed for connecting an electric motor with the gearing of the machine, and in the means employed for reversing the application of the current to said motor, as will be more fully understood from the subjoined specification and claims, and the accompanying drawings, which form a part of this specification.

In said drawing, Fig. 1 is a front elevation of the improved electrically-operated-can-testing machine embodying the invention; Fig. 2 a plan view of the same; Fig. 3 a side elevation; Fig. 4 a section on the line 4—4 of Fig. 1; Fig. 5 a detail partial view of the lever connections shown in Fig. 1; Fig. 6 a section on the line 6—6 of Fig. 4, being, however, upon a somewhat larger scale; Fig. 7 a section of the can holding mechanism taken on the line 7—7 of Fig. 1; Fig. 8 a section on the line, 8—8, of Fig. 7; Fig. 9 a section on the line 9—9 of Fig. 7; Fig. 10 a section on the line 10—10 of Fig. 7; and Fig. 11 a side elevation of the machine illustrating a modification of the driving gear connecting the motor with the can carriage.

In said drawing, 21 is the tank; 22 the cans to be submerged and tested mounted in the carriage 23; 24, 24 are vertical rods attached to the can carriage and sliding in the tubular guides 25. These rods, 24 may be furnished at their lower part with the racks, 26, 26, to mesh with pinions 27, 27, on the shaft, 28. This shaft, 28, carries the worm wheel, 29, engaging with the worm, 30, on the motor shaft 31. At each end of the carriage is pivoted a pitman rod, 32, connected to a counter-balance-lever, 33, carrying the weight 34. These weights, 34, counter-balance the carriage and facilitate its movement up and down by the power. In the modification shown at Fig. 11 the rack bars, 26, are omitted from the guide rods, 24, and a segmental worm gear, 291, substituted for the worm gear, 29, on the shaft 28. And in this modification the

counter-balance lever 33 instead of being mounted upon its own fulcrum, is connected to the shaft 28, and the power of the shaft 28 in said modification is applied to lift and lower the carriage through the counter-balance pitman, 32, as will be readily understood from the drawing. Projecting from the carriage, 23, is an arm, 35, to which is attached the vertical rod, 36, which moves up and down with the carriage and is provided with the upper stop or collar 37 and the lower stop or collar 38. A motor, 39, is mounted to drive the shaft 31.

40 is a common form of band brake, operated by means of the lever 41 to stop the motor. The lever 41 is carried between the jaws 42 of the brake and the outer end of said lever is lifted or lowered by the spring suspended arm 43, made forked and fitted with adjusting screws, 44, to permit a certain amount of play. The spring, 45, connected from this lever to the stationary frame of the machine serves to keep the forked lever normally raised. This forked lever 43 being connected to the shaft 46, and said shaft 46 connected by the arm, 47, and link 48 to the treadle, 49, the spring 45 maintains the treadle 49 in the lifted position, and the shaft, 46, in a normal position. Attached to the shaft 46, is an arm, 50, connected by a link, 51, to the bell-crank, 52, the other end of which bell-crank is connected to the switch-stem, 53, by a pin, 54, in the slot 55 in said stem. The upper end of the switch-stem is shown to be cylindric and passes through a guide 56, into the interior of the switch box 57, and at its upper end enters a second guide 58. Springs, 59, 60, tend to float or keep this switch stem in the position shown at Fig. 6, but leave it free to be moved up or down. On the stem, within the box, and floated on the springs 61, 61, are two electrical contact disks, 62, 63; and arranged in conjunction with these disks, in apposition, are the up terminals 65, 65, and the down terminals, 64, 64. When the contact disks stand in the position indicated in Fig. 6, there will be no current on the motor and the machine will be at a standstill. When the two contact disks 62 and 63 are pushed up into contact with the upper set of terminals, 65, the motor will turn in the direction to lower the carriage; while if said two disks are lowered into contact with the lower set of terminals, 110

64, the current will be reversed and the motor will turn in the direction to raise the carriage.

The operation is as follows: Suppose 5 the can carriage to be in its uppermost position and to have received the cans to be tested. The operator now puts his foot upon the treadle, 49, which through the connection, 48, and arm, 47, rotates the shaft, 46, causing the arm, 50, to move the bell-crank, 52, upward to the terminal of the slot, 54, in the switch stem, 53, and to then push up the said stem against its springs bringing the contact disks, 62, 63, 15 into contact with the upper terminals, 65, 65, which as before stated applies the current to the motor in such manner as to revolve said motor in a direction to cause the can carriage to descend. As the can carrier de- 20 scends the rod, 36, descends with it until the cans are submerged and the lower limit of movement reached, when the upper collar, 37, strikes the arm, 66, on the shaft, 46. Further downward movement rocks this 25 arm, 66, and the shaft 46 with it, lifting by aid of spring 45 the treadle, 49, and reversing the movement of the bell crank, 52. At the same time the reverse movement of the shaft, 46, swings the forked arm, 43, bringing 30 the strap-brake into action to stop the further rotation of the motor. Reverse movement of the bell crank, 52, causes the pin, 54, to leave the upper limit of the slot, 55, in the valve-stem and said stem, with 35 its floating contact disks, is lowered by the springs until said disks are brought into contact with the lower pairs of terminals, 64, 64, reversing the circuit through the motor, and starting it to revolve in such 40 direction as to cause the can carriage to be raised out of the tank at the same time the movement has released the strap-brake. When the carriage has reached its upper 45 limit of movement the collar, 38, will strike the arm, 66, and swing it far enough to permit the springs to restore the contact disks to normal or central position shown in Fig. 6. And things remain thus until the operator again depresses the foot treadle. 50 Having described the invention claim is made as follows:

1. In a can tester, in combination, a tank adapted to hold a liquid, a can carriage movable into and out of the tank, electrically controlled devices for operating said

can carriage, said devices having included therein a reversing switch having three positions, namely, forward, neutral and reverse, and means for operating said switch governed by the position of the can carriage. 60

2. In a can tester, in combination, a tank adapted to contain a liquid, a can carriage movable into and out of said tank, an electric motor adapted to move the can carriage, said motor being provided with electrical 65 circuits having included therein a switch provided with three positions, whereby the motor may be made to rotate forwardly, remain stationary or be reversed, said switch being in the form of a balanced stem 70 having two contact members thereon adapted to contact with two sets of oppositely connected terminals.

3. The can tester comprising an up and down moving can-carrier combined with an 75 electric motor and a three position electric switch, a lever connected to the switch by a slotted connection for setting the switch in the down position and an automatic trip device on the moving carrier for reversing the 80 position of the switch at the finish of the downward movement, substantially as specified.

4. The can tester comprising an up and down moving can-carrier combined with an 85 electric motor and a three position electric switch, a lever connected to the switch by a slotted connection for setting the switch in the down position and an automatic trip device on the moving carrier for reversing the 80 position of the switch at the finish of the downward movement, and a second trip device on said carrier for throwing the switch to the neutral position at the finish of the upward movement, substantially as 95 specified.

5. A can tester including, in combination, a tank, a movable can carrier for immersing the cans in a liquid contained in said tank; a pivotally mounted lever having a counter-balance weight on one end thereof; a pitman pivotally connected to the opposite end of said lever and to said carriage; and worm and worm gear mechanism for operating said lever and carrier, substantially as specified. 105
